UNITED STATES PATENT OFFICE.

SAMUEL MOLLENGARDEN, OF NEW YORK, N. Y., ASSIGNOR TO ROYAL IMPORTING CO., A COPARTNERSHIP OF NEW YORK, COMPOSED OF SAMUEL MOLLENGARDEN, WILLIAM SMITH, AND HARRY BERK, ALL OF NEW YORK, N. Y.

BEAD WIRE.

Application filed July 17, 1925. Serial No. 44,341.

To all whom it may concern:

Be it known that I, SAMUEL MOLLENGARDEN, a citizen of the United States, and a resident of the city of New York, borough of 5 Manhattan, in the county and State of New York, have invented a new and Improved Bead Wire, of which the following is a full, clear, and exact description.

This invention relates to bead wire and 10 more particularly to bead wire consisting of two or more strands of wire, said strands at one end being twisted together whereby a stiffened end is formed on one end of the wire to allow the threading of the beads 15 without the employment of a separate needle so that the bead wire in effect carries its own needle as an integral part thereof.

With this and other objects in view, the invention consists of certain novel features 20 of construction and combinations and arrangements of parts which will be more fully hereinafter described and pointed out in the claim.

In the accompanying drawings—

25 Figure 1 is a view, illustrating my improved bead wire in position around a cardboard holder or support, which is a convenient manner of commercializing the sale of the device;

30 Figure 2 is a fragmentary view in elevation, illustrating my improved bead wire.

My improved bead wire A consists of a plurality of strands of wire, and while I have illustrated two strands 1 and 2 it is 35 to be distinctly understood that I do not limit myself to the particular number of strands of wire other than at least two should be provided.

The bead wire may be of any desired 40 length and may have a coupling ring 3 attached to one end with a ring 4 for coupling engagement therewith, said ring 4 adapt-

ed to be secured to the other end of the bead wire after the beads are in position on the wire.

My invention resides broadly in providing a bead wire of this type consisting of a plurality of strands, the strands being tightly twisted together at one end as at 5, constituting an integral needle on the end 50 of the bead wire, so that the beads 6, illustrated by dot and dash line, may be positioned on the wire by projecting the twisted or needle portion 5 therethrough.

It will be noted that I employ my improved bead wire and dispense altogether with the necessity of a needle for threading the beads, and at the same time I provide a plurality of strands of wire which are secured together at both ends, the twisted 60 portion 5 constituting securing means at one end, and the other end of the bead wire being secured to the coupling ring 3 and twisted together as shown at 7, although, of course, I do not limit myself to the particular means for securing the coupling ring 65 to the bead wire.

Bead wire of this type may be coiled around a cardboard support 8 which constitutes a convenient means for supporting 70 the article and displaying the same for sale.

I claim:

A bead wire composed of a plurality of strands, said strands disconnected throughout the main portion of their lengths and 75 secured together at their end portions only, the securing means at one end comprising the twisting of said strands together throughout a portion of their length whereby a relatively stiff member is formed for threading beads on the wire without the use of 80 a separate needle.

SAMUEL MOLLENGARDEN.
